COMMUNICATION SYSTEM

Andrew J. Sorensen, Edgewood, Pa., assignor to
The Union Switch & Signal Company, Swiss-
vale, Pa., a corporation of Pennsylvania

Application December 16, 1933, Serial No. 702,751

10 Claims. (Cl. 246—63)

My invention relates to communication systems, and particularly to systems for communicating between two spaced locations on a train.

A feature of my present invention is the provision, in systems of this type, of apparatus which permits of both automatic control and telephone communication. A further feature of my invention is the provision of apparatus for establishing a characteristic frequency for each train of 5 a railway division, all similarly equipped. A still further feature of my invention is the provision of apparatus wherewith the equipment at the two locations may be set to respond only to each other, whereby a non-interfering system for each 10 train of a railway is obtained. Other features and advantages of my invention will appear as the specification progresses.

I will describe one form of apparatus embodying my invention, and will then point out the 15 novel features thereof in claims.

In the accompanying drawings, Figs. 1 and 2 when taken together constitute a diagrammatic view of one form of signaling apparatus embodying my invention. The apparatus of Fig. 1 is that installed at the location of the supervising operator, which, in this instance is on the locomotive. The apparatus of Fig. 2 is that installed at another location on the train. While the apparatus of Fig. 2 may be installed at any 20 point on the train, it will be referred to in the following description as being mounted in the caboose of a freight train. The communication circuit from one end of the train to the other may take different forms and preferably includes 25 the traffic rails in the manner described and claimed in the L. O. Grondahl application, Serial No. 450,135, filed May 6, 1930, on Electric train signaling systems.

Systems have been proposed for telephoning 30 between two spaced locations on a train, or between two trains, or between a wayside station and a train by transmitting from one location to the other a single side band of a carrier current modulated by the voice frequencies. In 35 my present system I propose to combine with such telephone system an automatic brake control which is normally active and which automatically transmits between the two locations control impulses consisting of a side band frequency of the carrier modulated by a predetermined intermediate frequency within a voice frequency range and which intermediate frequency has itself been first modulated with a desired control frequency 40 preferably below the voice frequency range. 45 That is to say, the carrier current during auto-

matic control is double modulated. The receiving equipment is effective to demodulate the transmitted side band and to also detect the control frequency. When telephone communication is established, the control apparatus is 5 rendered inactive and the carrier is modulated by the voice frequencies, the control condition in effect previous to the establishing of telephone communication being maintained unchanged. By such double modulation of a carrier current 10 a relatively large number of trains of a railway, all similarly equipped, can each be provided with a control system having a distinctive frequency channel without a change of the carrier frequency and with comparatively simple and reliable apparatus. This double modulation of the carrier is in effect a shifting of the carrier 15 frequency.

Although I am here disclosing a specific embodiment of my invention, it will be understood 20 that I do not wish to limit myself to brake control and telephone communication. My invention is equally useful to systems wherewith the operator of a leading locomotive governs the operation of a helper locomotive. Furthermore, it 25 will be understood that the automatic control may be used without the telephone equipment and that my invention is also equally useful for signaling from a wayside station to a train.

In each of the two views like reference characters refer to similar parts. 30

Referring to Fig. 1, the reference character EV designates the usual engineer's brake valve of standard type capable of establishing the release, running, lap, service and emergency conditions of the brake pipe pressure. A circuit 35 controlling contact assembly designated as a whole by the reference character CA is associated with the brake valve EV. As shown schematically, a contact member 4 is operatively connected with the brake valve handle 5 and is adapted to engage an arcuate contact 6 in both the release and running positions of the handle 5, a contact 7 in the lap position and an arcuate contact 8 in both the service and emergency positions of the handle 5. This contact assembly also includes a manually operated push button PB adapted to normally close a contact 9 and to close a contact 10 when depressed, the push button being of the spring return type. 40 45 50

Located on the locomotive is a generator GI of alternating current adapted to supply different frequencies in accordance with the different positions of the contact assembly CA. As here shown, this generator GI is of the vacuum tube type 55

and comprises an electron tube 61 and its associated circuits. The tube 61 contains the usual heated filament 12, a grid 13 and a plate 14, one side of the filament being preferably connected with a ground electrode 36. The tube 61 is provided with a plate circuit including an iron core reactor 15 and a source of current not shown, the positive terminal of which source is indicated at B and the negative terminal of which is 10 grounded for completing the plate circuit through the ground electrode 36. The tube 61 is also provided with a grid circuit including a condenser 37, a grid leak unit 16, a coupling condenser 17 and a tuned oscillating circuit consisting of the primary winding 18 of a transformer T1 and a suitable condenser 20, 22, 23 or 24, to be inserted into the circuit in accordance with the position of the contact assembly CA. Condensers 20, 22, 23 and 24 are of different capacities and 20 are adapted to be inserted into the oscillating circuit in the following manner. With the handle 5 set at either the release or running position and the contact member 4 engaging the contact 6, this oscillating circuit can be traced from the lower 25 terminal of the primary winding 18 along wire 19, condenser 20, contact 6, contact member 4, contact 9 of the push button PB and wire 21 to the top terminal of the primary winding 18. With the handle 5 moved to the lap position and the 30 contact member 4 engaging the contact 7, the condenser 22 is inserted into this oscillating circuit, and with the handle 5 moved to either the service or emergency positions, the condenser 23 is selected. Depressing the push 35 button PB at any time connects the condenser 24 with the oscillating circuit. It will be assumed that the condenser 20 has such capacity as to produce oscillations of a frequency of 20 cycles per second, the condenser 22 a frequency of 30 cycles 40 per second, the condenser 23 a frequency of 40 cycles and the condenser 24 a frequency of 10 cycles. It will be understood, of course, that other frequencies could be chosen and that the above frequencies are given by way of illustration only. 45 It follows that the release and running positions of the brake valve EV are accompanied by generator G1 producing a frequency of 20 cycles per second, the lap position of the valve is accompanied by a frequency of 30 cycles per second, 50 the service and emergency positions of the valve by a frequency of 40 cycles and that the depressing of the push button PB at any time is accompanied by the generator G1 supplying a current of 10 cycles per second. In each case an electromotive force of corresponding frequency will be induced in the secondary winding 25 of the transformer T1. The function of these several low frequency currents supplied by the generator G1 in accordance with the position of the brake valve EV and the push button PB will appear hereinafter.

The equipment of Fig. 1 includes a three-position master switch MS. This master switch MS is manually operated to any one of three positions 65 indicated on the drawings by the numerals 1, 2 and 3. The position No. 1 is the normal position to which the switch returns under the action of a biasing spring not shown when not actually held manually in one of the other two positions. 70 When the switch occupies its No. 1 position, automatic control of the train brakes is effected, as will appear as the specification progresses. The No. 2 position is used when it is desired to transmit a telephone message from the locomotive, and the No. 3 position is used when it is 75

desired to receive a telephone message on the locomotive. Consequently, the locomotive equipment can be shifted to any one of the three conditions, automatic brake control, speech sending or speech receiving at the discretion of the locomotive operator. 5

The equipment of Fig. 1 also includes a manually operated selector S1. As shown schematically, two manually operated contact members 41 and 71 are connected together for being actuated 10 in step with each other and are adapted to be set in any one of five different positions as will be understood by an inspection of Fig. 1. Associated with the contact member 41 are five condensers 34^a, 34^b, 34^c, 34^d and 34^e, of different 15 capacities which are selected according to the position of the member 41. In like manner the contact member 71 selects any one of five condensers 72^a, 72^b, 72^c, 72^d and 72^e of different 20 capacities according to its position. As will appear hereinafter, the frequency channel on which a train is operated is determined by the position of the contact members 41 and 71 of the selector 25 S1. Hence, in this instance, any one of five different frequency channels can be selected for the train.

Located on the locomotive is a second electron tube 26 which is adapted to at times function as an amplifier and at other times as an element of an oscillator indicated as a whole by the reference 30 character G2. The tube 26 contains a heated filament 27, a grid 28 and a plate 29, one side of the filament being preferably connected with a ground electrode 30. A plate circuit is provided including the upper portion of the primary winding 31 of a transformer T2 and the source of current, the positive terminal of which source is indicated at B and the negative terminal of which is grounded as pointed out hereinbefore. The lower terminal of the primary winding 31 is connected with the grid 28 over wire 40, contact 39 of the master switch MS in its No. 1 position and wire 38. In accordance with the varying position of contact member 41, a different one of the condensers of the selector S1 is connected across the 35 primary winding 31 as can be traced from the lower terminal of that winding along wire 40, contact member 41, any one of the group of condensers 34^a, 34^b, 34^c, 34^d and 34^e according to the 40 position of the member 41, wire 44, contact 35 of the master switch MS in its No. 1 position and wire 45 to the top terminal of the primary winding 31. By proper proportioning of the number 45 of turns of the primary winding 31 and the capacity of the condenser 34^c, which is the condenser selected as illustrated in Fig. 1, this circuit 50 system will oscillate at any suitable frequency, which I shall assume to be 1000 cycles per second. Each of the remaining condensers 34^a, 34^b, 34^d and 34^e is so proportioned that when inserted 55 in the circuit with the primary winding 31 a different frequency is generated. Hence, the oscillator G2 can be made to produce any one of five different frequencies according to the setting 60 of the contact member 41. As stated above, I shall assume the frequency of the oscillator G2 to be 1000 cycles per second when the condenser 34^c is selected as illustrated in the drawings. The 65 other frequencies I shall assume to vary from 1000 cycles and to vary from each other by a sufficient number of cycles per second to provide five different frequency channels. It will be noted, however, that these several different frequencies of 70 oscillator G2 will preferably fall within the usual 75

voice frequency band which band I shall refer to as extending from 500 to 2500 cycles.

The oscillations of the oscillator G2 are modulated by the output of the generator G1 in the following manner. The secondary winding 25 of the transformer T1 has its upper terminal connected with the ground electrode 36 through a condenser 46 and has its lower terminal connected with the oscillating system over wire 47, 10 contact 48 of the master switch in its No. 1 position, a reactor 49 and wire 50. This modulating circuit will easily be recognized as a form of the Heising modulation circuit. It follows that with the selector S1 set in the position illustrated in 15 Fig. 1 and the master switch MS occupying its No. 1 position, the oscillator G2 supplies a current of 1000 cycles modulated at the low frequency of 10, 20, 30 or 40 cycles according to the position of the brake valve handle 5 and the push button 20 PB, and this modulated current will induce an electromotive force of corresponding frequency in the secondary winding 51 of the transformer T2.

At other times the electron tube 26 functions 25 as an amplifier and to this end the grid 28 of the tube 26 is provided with a circuit including the secondary winding 32 of a transformer T3 and a battery 33. The primary winding 42 of the transformer T3 is included in a circuit which also contains a battery 43, a microphone M and the contact 35 of the master switch MS when moved to its No. 2 position. It is to be seen, therefore, that when the master switch MS is shifted from its No. 1 to its No. 2 position, the tube 26 no longer functions as an element of an oscillating system but functions as an amplifier of the voice frequencies developed by speaking into the microphone M and applied to the grid 28 through the medium of the transformer T3, the oscillating system being now open at the contacts 35 and 39 and the modulating circuit being open at the contact 48 of the master switch. These voice frequencies will appear in the plate circuit of tube 26 greatly increased in amplitude and will induce an electromotive force of corresponding frequencies in the secondary winding 51 of the transformer T2. That is to say, with the selector S1 set in the position illustrated in the drawings and the master switch MS occupying the No. 1 position, there will be induced in the secondary winding 51 of the transformer T2 an electromotive force having a frequency of 1000 cycles modulated at the frequency of 10, 20, 30 or 40 cycles according to the position of the handle 5 and the push button PB; and that with the switch MS moved to its No. 2 position, there will be induced in the secondary winding 51 an electromotive force corresponding to the voice frequencies developed in the microphone M and amplified by the electron tube 26. As stated above, these voice frequencies will be assumed to extend over a band from 500 to 2500 cycles.

The secondary winding 51 of the transformer T2 is connected with the input of a balanced modulator oscillator BMO adapted to generate a carrier frequency of say, 7000 cycles per second. This balanced modulator oscillator BMO may take different forms, such for example as two vacuum tubes connected to oscillate in parallel, and is here shown conventionally only for the sake of simplicity as its specific structure forms no part of my invention. A preferred type of such oscillator is described in a copending application for Letters Patent, Serial No. 658,932, filed Feb. 28, 1933, by Leland D. Whitelock et al.

for Communication systems. It is deemed sufficient for this description to say that the output of the modulator oscillator BMO contains the side bands of the modulated carrier with the carrier suppressed. Thus, the output of the modulator oscillator BMO consists of an upper side band 5 of 8000 cycles modulated at 10, 20, 30 or 40 cycles and a lower side band of 6000 cycles modulated at 10, 20, 30 or 40 cycles during automatic control; and consists of an upper side band extending from 7500 to 9500 cycles and a lower side band extending from 4500 to 6500 cycles during telephone communication. Both the upper and the lower side band frequencies of the modulator oscillator BMO are impressed upon a filter F2 10 which is adjusted to pass one side band and suppress the other, the upper side band being preferably passed. The upper side band passed by the filter F2 is impressed upon the input of an amplifier transmitter AT preferably consisting of 20 two power tubes operated in the conventional push-pull manner, and is amplified to a relatively high energy level and then passed to an output transformer T4. The specific type of neither the filter F2 nor the amplifier transmitter AT 25 forms a part of my invention and these devices are shown by a symbol only in order to simplify the drawings as much as possible.

It follows from the foregoing description of the transmitting equipment on the locomotive that 30 under the No. 1 position of the master switch MS the carrier current of 7000 cycles will be double modulated by the channel frequency of 1000 cycles and the signaling frequency of 10, 20, 30 or 40 cycles as the case may be. The carrier and the 35 lower side band will be suppressed, leaving the upper side band consisting of 8000 cycles plus the signaling frequency to be delivered to the secondary winding 52 of the output transformer T4. With the master switch MS shifted to its 40 No. 2 position and the operator speaking into the microphone M, current will be transmitted to the secondary winding 52 of the output transformer T4 consisting of the upper side band of the carrier frequency plus voice frequencies, in this instance 45 a band extending from 7500 to 9500 cycles. The setting of the selector S1 to a position to select one of the other condensers 34^a, 34^b, 34^d or 34^e will change the channel frequency and in turn cause a corresponding change in the upper side 50 band supplied to the secondary winding 52 under the control condition. The output of the secondary winding 52 will be delivered to the communication circuit in a manner to now be described.

The reference character N designates a mechanically tuned coder. This coder N may take any one of many forms well known to the art and preferably is that disclosed in the Letters Patent No. 1,858,876, issued May 17, 1932, to P. N. 60 Bossart, on Coding apparatus. It is deemed sufficient for this description to say that the winding 53 of the coder N is energized from a battery 54 over its own contact 55 and as long as so energized, a contact member 56 is oscillated between 65 two contacts 57 and 58 at a frequency of say, 60 cycles per minute. In other words, the contact member 56 alternately makes engagement with the contacts 57 and 58 during alternate one-half second intervals.

59 and 60 are inductor coils mounted on the locomotive in inductive relation with the traffic rails 11 and 11^a, respectively, which rails are included in the communication circuit. By means of these inductor coils 59 and 60 energy is trans- 75

mitted to and received from the communication circuit by the locomotive apparatus and to this end these coils are connected either to the output circuit of the transmitting equipment or to the 5 input circuit of the receiving equipment. With the master switch MS occupying its No. 1 position, the coils 59 and 60 are connected with the secondary winding 52 of the output transformer T4 each one-half second interval the contact 10 member 56 of coder N engages the contact 58. This circuit can be traced from the top terminal of the secondary winding 52 through a tuning condenser 62, wire 63, contact 56—58, contact 64 of the master switch, coils 60 and 59 in series, 15 ground electrode 65 and thence by a ground electrode 66 to the lower terminal of the secondary winding 52. During the half second interval that the contact member 56 engages the contact 57 the coils 59 and 60 are disconnected from the 20 output transformer T4 and are connected with the input circuit of the receiving equipment to be shortly described, the input circuit including a filter F1 and a ground electrode 67, as well as the coder contact 66—57 and the contact 64 of the 25 master switch as will be understood by an inspection of Fig. 1. When the master switch MS is shifted to its No. 2 position, the contact 64 shunts around the coder contact 56—58 and the inductor coils 59 and 60 are connected directly 30 with the output transformer T4, while, when the switch MS is shifted to its No. 3 position, the contact 64 shunts around the coder contact 56—57 and connects the coils 59 and 60 directly with the input filter F1. It follows that under the 35 No. 1 position of the master switch the transmitting and receiving equipments on the locomotive are alternately coupled with the communication circuit for periods of one-half second through the medium of the coder N. The transmitting equipment is continuously coupled with the communication circuit when the switch MS is shifted to its No. 2 position and the No. 3 position of the master switch is effective to continuously couple the circuit with the receiving 40 equipment.

In the form here shown, the receiving equipment of Fig. 1 comprises the filter F1, an amplifier A1, a demodulator D, a filter F3, a second amplifier A2 and an amplifier detector A3. Inasmuch as such devices are well-known to the art and the specific structure of none of them forms a part of my invention, they are each shown by a symbol only in order to simplify the drawings and make them more readily understood. This 55 receiving equipment will now be described.

The input filter F1 is preferably adjusted so as to pass a frequency band of 7500 to 9500 cycles and to attenuate all other frequencies. That is, the input filter F1 of the receiving equipment is 60 adjusted to pass a frequency band corresponding to the upper side band of a carrier of 7000 cycles modulated by voice frequencies. In the form of my invention here shown the equipment at a location is preferably arranged to both send and 65 receive on the same carrier frequency and also on the same channel frequency. This means that the frequency band sent out by the apparatus at the other location to be described later, and to which the receiving equipment on the locomotive 70 is to respond is the same as that sent out by the transmitting equipment on the locomotive as previously described. The current passed by the filter F1 is impressed upon the amplifier A1 which amplifies the above-mentioned frequency band 75 and passes it on to the balanced demodulator D

where the received frequency band is combined with a carrier of 7000 cycles originating in D with the result that the output of the demodulator D contains an upper and a lower side band. The lower side band consists of the received frequencies less 7000 cycles, that is, frequencies within the band between 500 and 2500 cycles. It is to be noted that this lower frequency band is the same band impressed upon the balanced modulator oscillator BMO of the transmitting equipment. 10 The upper side band consists of the received frequencies plus 7000 cycles.

The output of the demodulator D is passed through the band pass filter F3 adjusted so as to pass the lower side band of 500 to 2500 cycles and 15 to exclude the upper side band. The current passed by the filter F3, therefore, contains frequencies only within the voice frequency range and these frequencies are then in turn impressed upon the input of the amplifier A2 where they are 20 caused to appear in the output of that amplifier greatly increased in amplitude.

During such time as the master switch MS occupies its No. 1 position, the output of the amplifier A2 includes a tuned circuit network and at such 25 time as the switch MS is shifted to its No. 3 position, the output of the amplifier A2 is connected with the operating winding of a loud speaker. This tuned circuit network can be traced from the upper right-hand terminal of amplifier A2 30 along wire 68, contact 69 of the master switch MS in its No. 1 position, a reactor 70, contact member 71 of the selector S1, condenser 72^a, wire 71, input of the amplifier detector A3 and thence by wire 78 to the lower right-hand terminal of the amplifier A2. At such time as the master switch MS is shifted to its No. 3 position the output of the 35 amplifier A2 includes wire 68, contact 69, operating winding of a loud speaker LS, a ground electrode 79 and thence by a ground electrode 80 and 40 wire 78 to the lower right-hand terminal of the amplifier A2. The parts of the tuned circuit network just traced are so proportioned and adjusted as to respond to a frequency band extending from 1010 to 1040 cycles, that is, to a band equal to 45 the channel frequency of 1000 cycles modulated at the signaling frequencies of 10, 20, 30 and 40 cycles. The other condensers 72^a, 72^b, 72^c and 72^d associated with the contact member 71 are of such capacity as to cause this tuned output circuit of 50 amplifier A2 to respond to other channel frequencies plus the signaling frequencies. The arrangement is such that preferably the condenser selected by the contact member 71 tunes this output circuit of the amplifier A2 to respond to 55 the same channel frequency as the condenser selected by the contact member 41 in the same corresponding position established for the oscillator G2, it being recalled as stated above, that the equipment at a location is preferably arranged to both send and receive on the same channel frequency. The circuit including the operating winding of the loud speaker LS is non-tuned and hence all the voice frequencies passed to the output of the amplifier A2 will be reproduced by the 60 loud speaker LS.

The amplifier detector A3 acts as a detector of the channel frequency and also amplifies the signaling frequency component with which it is modulated, the signaling frequency being passed 65 to the primary winding 73 of a transformer T5. The secondary winding 74 of the transformer T5 is connected with tuned circuit networks 75 and 76. A portion of the network 75 is connected with the input terminals of a full-wave rectifier 81, the 75

5 output terminals of which are connected with the winding of a relay 82. In like manner a portion of the network 76 is connected with the input terminals of a rectifier 83, the output terminals of which are connected with the winding of a relay 84. The networks 75 and 76 are tuned to resonance at the frequencies of 30 and 10 cycles, respectively.

10 It follows from the foregoing description of the receiving equipment on the locomotive that when the upper side band of a carrier of 7000 cycles double modulated at 1000 cycles and 30 cycles is impressed upon the receiving equipment and the master switch occupies its No. 1 position, the side 15 band is filtered, demodulated, amplified and then impressed upon a tuned circuit responsive to the frequency of 1030 cycles and which includes the input of the amplifier detector A3. The amplifier detector A3 detects the channel frequency of 1000 20 cycles and causes to appear in its output a frequency of 30 cycles only. This signaling frequency is impressed upon the tuned circuit 75 and the relay 82 is energized. In the event the channel 25 frequency of 1000 cycles has been modulated at the signaling frequency of 10 cycles a current of 10 cycles appears in the output of the amplifier detector A3 and the relay 84 is energized. Relay 82 controls at its front contact 85 a simple circuit 30 for a signal lamp 86 and the relay 84 controls at its front contact 87 a circuit for a signaling device here shown as a bell 88. When the master switch is shifted to its No. 3 position, the output of the amplifier A2 is shifted to the operating winding of the loud speaker LS and upper side band frequencies 35 corresponding to the carrier modulated at voice frequencies impressed upon the input of the receiving equipment will be filtered, demodulated, amplified and reproduced by the loud speaker LS.

40 Referring now to Fig. 2, the caboose is provided with a master switch MS and a selector S1 identical to the corresponding devices of Fig. 1. The caboose is also provided with transmitting and receiving equipments similar to the corresponding equipment on the locomotive. It is deemed unnecessary to repeat the description of these various devices in detail except to point out their modifications. The generator G1 of the transmitting equipment of the caboose is the 45 same as the generator G1 on the locomotive except only two condensers 89 and 90, of different capacities, are provided for its oscillating circuit, the condenser 89 being normally inserted into the circuit over a normally closed contact 50 123 of the push button PB and the condenser 90 being connected into the circuit when the push button is depressed and its contact 124 closed. I shall assume that oscillations of 30 cycles per second are produced when the condenser 89 is 55 included in the oscillating circuit and that the oscillations are of a frequency of 10 cycles when the condenser 90 is selected.

60 The electron tube 26 of Fig. 2 serves at times as an element of an oscillating system and at other times as an amplifier of voice frequencies developed by speaking into the microphone M. The frequencies developed by the oscillator G2 when the condenser 34^c is selected by the associated selector S1 as illustrated in Fig. 2 is preferably 65 1000 cycles per second the same as described for the corresponding apparatus on the locomotive. As long as the master switch MS on the caboose occupies its No. 1 position this channel frequency is modulated by the 30 or 10 70 cycles of the generator G1 over the modulated

75 circuit including the contact 48 of switch MS. With the master switch MS shifted to its No. 2 position, the oscillating and modulating circuits associated with tube 26 are opened at the contacts 35, 39 and 48, and the microphone M is 5 connected with the primary winding 42 of the associated transformer T3 and the tube 26 functions as an amplifier of the voice frequencies developed by speaking into the microphone M. Hence, electromotive forces having a frequency 10 corresponding to the channel frequency of 1000 cycles modulated at the frequency of either 30 or 10 cycles, or voice frequencies produced in the microphone are induced in the secondary winding 51 of the transformer T2 of the caboose 15 transmitting equipment in precisely the same manner as induced in the secondary winding 51 of the transformer T2 on the locomotive. The secondary winding 51 of the caboose transformer T2 is connected with a balanced modulator 20 oscillator BMO preferably similar to the corresponding device of Fig. 1. Consequently, side band frequencies of a carrier of 7000 cycles double modulated at the channel and signaling frequencies or modulated at the voice frequencies 25 appear in the output of the modulator oscillator. The filter F2 and amplifier transmitter AT of Fig. 2 are preferably similar to the corresponding devices on the locomotive and thus there is produced in the secondary winding 52 30 of the associated output transformer T4 the upper side band only amplified to a relatively high energy level. The other condensers associated with the contact member 41 of the caboose selector S1 are preferably of the same respective 35 capacities as the corresponding condensers associated with the contact member 41 of the selector on the locomotive so that corresponding positions of the two selectors cause the associated transmitting equipments to operate on 40 like channel frequencies. The manner of transferring the energy supplied to the secondary winding 52 of the caboose output transformer T4 to the communication circuit will be pointed out later in the description. 45

The filter F1, amplifier A1, demodulator D, band pass filter F3, amplifier A2 and amplifier detector A3 of the caboose receiving equipment, all may be and preferably are similar to the respective devices on the locomotive. 50

91 and 92 are inductor coils mounted on the caboose in inductive relation with the traffic rails 11 and 11^a, respectively, and these coils serve as the medium for transferring energy from the caboose transmitting equipment to the communication circuit and from the communication circuit to the caboose receiving equipment. 55

That the apparatus of Fig. 2 may be coupled with the communication circuit in step with the apparatus of Fig. 1, two synchronizing relays 95 60 and 101 are controlled by the receiving equipment of Fig. 2 and in turn govern its output circuit in the following manner. At the start, current picked up from the traffic rails at the caboose will be impressed on the filter F1 through 65 a circuit which can be traced from the right-hand terminal of the coil 92 over contact 93 of the master switch MS in its No. 1 position, back contact 94 of the relay 95, filter F1, ground electrode 96 and thence by ground electrode 97 to the left-hand terminal of the coil 91. As outlined 70 in connection with the description of the apparatus of Fig. 1, the control impulse supplied to the traffic rails consists of the upper side band of the carrier double modulated by the channel and 75

signaling frequencies, and this side band when impressed upon the receiving equipment through the filter F^1 is filtered, demodulated and amplified and a frequency corresponding to the channel frequency modulated by the signaling frequency is made to appear in the output of the amplifier $A2$. Therefore, there will appear in the output of the amplifier $A2$ of Fig. 2 the channel frequency, in this instance 1000 cycles, modulated by one of the signaling frequencies. This output circuit for the caboose amplifier $A2$ can be traced from the upper right-hand terminal of the amplifier $A2$ along wire 98 , contact 99 of the master switch in its No. 1 position, one side of a full-wave rectifier 100 , winding of the relay 101 , the other side of the rectifier 100 , reactor 70 , contact member 71 of the selector $S1$, condenser 72^a , wire 103 , input of the amplifier detector $A3$ and thence to the lower right-hand terminal of the amplifier $A2$. This circuit being tuned through the medium of the reactor 70 and condenser 72^a to respond to the channel frequency of 1000 cycles, it follows that the relay 101 will be energized in response to this control impulse when impressed upon the input circuit. Relay 101 on picking up closes at its front contact 104 a simple circuit for the relay 95 and that relay will be energized. Relay 95 on picking up opens the above traced input circuit to the filter F^1 at the back contact 94 but that circuit is now completed at the front contact 105 of the relay 101 and hence both relays 95 and 101 remain picked up as long as the incoming control current is received. It will be recalled that a control impulse is transmitted to the traffic rails by the locomotive apparatus for a period of one-half second as determined by the coder N , and thus the relays 95 and 101 will be energized for approximately an interval of one-half second. When the incoming impulse ceases, the relay 101 immediately drops but the relay 95 remains picked up for an interval, approximately one-half second, inasmuch as it is slow releasing in character. During the slow release period of the relay 95 , the inductor coils 91 and 92 are connected with the secondary winding 52 of the output transformer $T4$, the circuit extending from the right-hand terminal of the coil 92 over contact 93 , back contact 106 of relay 101 , front contact 107 of relay 95 , wire 125 , tuning condenser 62 , secondary winding 52 , ground electrode 66 and thence by the ground electrode 67 to the left-hand terminal of the coil 91 . It is to be seen, therefore, that following the receipt of an impulse of control current on the caboose the inductor coils are connected with the output of the transmitting equipment and an impulse of current consisting of the upper side band of the carrier double modulated at the frequency of 1000 cycles and 30 cycles is supplied to the traffic rails. As soon as the relay 95 releases, the transmission stops and the caboose receiving equipment is again connected with the inductor coils 91 and 92 ready to receive the next impulse transmitted from the locomotive. Hence, the caboose receiving and transmitting equipments will be alternately coupled with the communication circuit in synchronism with the locomotive equipments. It will be noted that with the master switch MS of Fig. 2 shifted to its No. 2 position, the inductor coils 91 and 92 are connected directly with the output transformer $T4$ over contact 93 and wires 102 and 125 , and with the switch MS shifted to its No. 3 position, the filter

F^1 is connected directly with the inductor coils over the contact 93 .

As stated above, the output circuit for the amplifier $A2$ of Fig. 2 including the condenser 72^a and the input of the amplifier detector $A3$ is so proportioned and adjusted as to respond to a current of 1000 cycles modulated at a signaling frequency of 10, 20, 30 or 40 cycles. The associated amplifier detector $A3$ detects this channel frequency and causes to appear in its output, which includes the primary winding of an associated transformer $T5$, the signaling frequency only. The secondary winding 14 of the transformer $T5$ is connected with the tuned circuits 108 , 109 , 110 and 111 tuned to respond to 20, 30, 40 and 10 cycles, respectively. A portion of the circuit network 108 is connected with the top winding of a relay 112 through a full-wave rectifier 113 and in like manner portions of the circuits 109 , 110 and 111 are connected with relays 114 , 115 and 116 , respectively, through the respective rectifiers 117 , 118 and 119 . Consequently, the relays 112 , 114 , 115 and 116 will be energized when the control current contains the signaling frequencies of 20, 30, 40 and 10 cycles, respectively.

The relays 112 , 114 , 115 and 116 may be utilized for selectively governing a control and signaling mechanism in any desired manner and in the form here shown they control the different positions of an auxiliary brake controlling mechanism and a signaling device. The caboose is provided with a brake controlling mechanism including a main reservoir MR , a feed valve FV and three electropneumatic valves RV , LV and SV ; and a signaling device 126 . The caboose, of course, will also be equipped with a compressor and all other apparatus necessary to insure an ample supply of air pressure in the main reservoir MR independent of the usual supply of air pressure on the locomotive. The valves RV and SV are each biased to the closed position and each is lifted to the open position when the associated magnets 120 and 121 , respectively, are energized. The valve LV is biased to the open position and is held closed when its magnet 122 is energized. When the valve RV is open, the brake pipe BP is connected to the feed valve FV and the auxiliary brake controlling mechanism reproduces the running condition of the engineer's brake valve EV on the locomotive. When either the valve SV or LV is open, the brake pipe BP is connected to the atmosphere through a vent of such characteristics as to produce a reduction in brake pipe pressure at substantially the service rate of reduction of the usual brake valve to effect a service application of the train brakes. When the valve LV is held closed and the valves RV and SV are closed due to their bias, both the supply and exhaust of the brake pipe are closed and the auxiliary brake controlling mechanism reproduces the lap condition of the engineer's brake valve.

When the relay 112 is energized, current will flow from the positive terminal of a current source over the front contact 127 of that relay and through the magnets 120 and 122 in series to the other terminal of the current source, and both magnets 120 and 122 will be energized to open valve RV and to hold closed the valve LV with the result that the running condition of the brake pipe pressure will be established. When the relay 114 is energized, current will flow from the current source over the front contact 128 of that relay and through the magnet 122 to the opposite terminal of the current source, and magnet 122

will be energized with the result that the valve LV is held closed and the lap condition of the brake pipe pressure will be established. When the relay 115 is energized, current will flow from the current source over the front contact 129 of that relay and through the magnets 121 and 122 in series to the opposite terminal of the current source, and these two magnets will be energized with the result that the valve LV will be closed and the valve 10 SV will be open and the service application condition of the brake pipe pressure will be established. In the event all three of the relays 112, 114 and 115 become deenergized, the magnet 122 will be without current and the valve LV will be 15 open to establish a brake applying condition of the brake pipe pressure, so as to provide the closed circuit principle for the apparatus. With the relay 116 energized, current will flow over a simple circuit including its front contact 130 and the bell 126 and the bell will be sounded. Each of the relays 112, 114 and 115 is provided with a second winding and a stick circuit easily traced. Consequently, when the caboose operator shifts the master switch MS to either its No. 2 or No. 3 20 position, the contact 131 completes the connection to the current source and current will flow to the stick circuit of whichever of the relays 112, 114 and 115 happen to be energized at the time and that relay will be held picked up notwithstanding 25 standing energy is no longer supplied over the respective tuned circuit network. The relay 116 which responds to the 10 cycle signaling current is provided with a second front contact 132 which is effective when closed to supply current to the 30 stick circuits for the other relays 112, 114 and 115. Hence, a signaling current of 10 cycles is effective to not only sound the bell 126 but to also retain 35 energized whichever of the relays 112, 114 and 115 happen to be picked up with the result that the established condition of the auxiliary brake 40 controlling mechanism remains unchanged.

In describing the operation of my system I shall first describe the automatic control and then point out the manner whereby the operators at 45 the two locations may establish telephone communication. Furthermore, I shall assume that the master switches at each of the two locations normally occupy the No. 1 position and that the two selectors are set in the position illustrated 50 in the drawings. Under these circumstances and with the brake valve handle 5 moved to either the release or running position, the generator G1 on the locomotive supplies current of 20 cycles with which the channel frequency of 1000 cycles 55 is modulated, and the carrier in turn is modulated by this combination. The control impulses transmitted to the traffic rails each one-half second interval that the output circuit is connected with the inductor coils by the coder N will consist of 60 the upper side band frequency of 8020 cycles. Such an impulse when picked up at the caboose will be applied to its input circuit, causing the two synchronizing relays 95 and 101 to be picked up and also causing a current of 20 cycles to appear 65 in the output of the associated amplifier detector A3. Relay 112 will respond to this 20 cycle current and the running condition of the auxiliary brake controlling mechanism will be established. At the end of the one-half second 70 interval of this impulse the coder N transfers the inductor coils on the locomotive from the transmitting circuit to the receiving circuit. The relays 95 and 101 on the caboose will now function to transfer its inductor coils from its receiving 75 circuit to its transmitting circuit and a return

impulse consisting of the carrier double modulated by the channel frequency of 1000 cycles and the signaling frequency of 30 cycles will be supplied to the traffic rails. This return impulse consisting of the upper side band frequency of 5 8030 cycles will be picked up at the locomotive, filtered, demodulated, amplified and detected, causing to appear in the output of the associated amplifier detector A3 a current of 30 cycles, and the relay 82 will be energized. Relay 82 on picking up will cause the signal lamp 86 to be displayed to indicate to the locomotive operator that the impulse transmitted from the locomotive has been received at the caboose and that the apparatus at that location is in working order. 10 As long as the handle 5 remains in the running or release position, these control and return impulses will be alternately exchanged between the two locations with the result that the running condition of the auxiliary brake controlling 15 mechanism will be maintained in effect and the signal lamp 86 on the locomotive will be displayed.

In the event the locomotive operator moves his brake valve handle 5 to either the service or emergency position, the signal frequency generated on the locomotive is shifted from 20 cycles to 40 cycles and the side band frequency is shifted from 8020 to 8040 cycles. The impulses now picked up at the caboose will cause to appear in the output of the amplifier detector A3 25 current of 40 cycles and the relay 115 will be energized and an automatic brake application will be effected. The return impulses transmitted from the caboose will still contain the signal frequency of 30 cycles and hence the signal lamp 86 on the locomotive will remain displayed indicating to the locomotive operator that the control impulses are being received at the caboose and that the apparatus at that point is 30 in working order. Should the operator shift his 40 handle 5 to the lap position, the channel frequency will be modulated at the signal frequency of 30 cycles and the side band transmitted will consist of 8030 cycles. This impulse when picked up at the caboose will cause to appear in the output of the amplifier detector a current of 30 45 cycles and the relay 114 will be energized with the result that the lap condition of the auxiliary brake controlling mechanism will be established. Again, the return impulses will contain the signal 50 frequency of 30 cycles and the signal lamp 86 will still be displayed. It is to be seen, therefore, that the automatic control will be effective to cause the condition of the auxiliary brake controlling mechanism to register with the position 55 of the engineer's brake valve and in each position an indication will be provided on the locomotive informing the operator that the system is operating properly.

If the train is to operate on a channel frequency other than 1000 cycles, each operator will set his selector S1 at one of its other positions, the two selectors being set at corresponding positions so that the equipment at each location will operate on the same channel frequency. In the form of my invention here disclosed five different channel frequencies are available and hence five different trains can be operated on the railway with each train provided with a non-interfering control system. It is clear that the 65 selectors can readily be provided with additional positions and additional condensers having different capacities connected therewith with the result that other trains could be provided with 70 75

a distinctive channel frequency should it seem desirable to do so.

Since ordinarily an automatic volume control is used in the amplifier A1, the input energy to the amplifier detector A3 is substantially the same no matter which of the channel frequencies is used. The tuned circuit consisting of the reactor 70 and the condenser selected by the contact member 71 can therefore be comparatively simple in construction. Thus, it is evident that the principle of double modulation of the carrier for obtaining a characteristic channel frequency for each of a relatively large number of trains permits a comparatively simple filter arrangement.

I shall now assume that the operator on the locomotive desires to telephone to the operator in the caboose. The locomotive operator will first depress his push button PB, causing the generator G1 at that location to supply a signaling current of 10 cycles for modulating the channel frequency. The transmitted impulse will now contain a side band frequency of 8010 cycles and the relay 116 of the caboose apparatus will be picked up and the signal bell 126 will be sounded, calling the caboose operator's attention to the fact that telephone communication is desired. As pointed out hereinbefore, relay 116 when energized is effective to retain picked up whichever one of the control relays 112, 114 and 115 happens to be energized at the time and hence no change will take place in the condition of the brake controlling mechanism as the result of this signaling frequency of 10 cycles. The operator at the caboose will now shift his master switch MS to its No. 2 position and speak into his microphone M a prearranged remark that he is ready for telephone communication. In the meantime the locomotive operator shifts his master switch to its No. 3 position so that the remark transmitted from the caboose operator will be sounded by the loud speaker on the locomotive. From this point on the two operators will talk back and forth each shifting his master switch to either its No. 2 or No. 3 position according as to whether he is speaking into the microphone or is listening to the loud speaker. At the end of the telephone conversation each operator will release his master switch permitting it to return to its No. 1 position so that the automatic control will be at once reestablished. It is to be noted that the No. 2 and No. 3 positions of the master switch on the caboose will be effective to maintain the condition of the brake controlling mechanism during the telephone conversation.

In the event the caboose operator desires to telephone to the locomotive operator he will depress his push button PB causing the generator G1 to supply a current of 10 cycles with the result that the return impulses now contain the side band frequency of 8010 cycles and the relay 84 on the locomotive will be energized. With the relay 84 picked up, the bell 88 will be sounded, calling the locomotive operator's attention to the fact that telephone communication is desired. The locomotive operator will now shift his master switch to its No. 2 position and speak the prearranged remark into the microphone M and the caboose operator will shift his master switch to its No. 3 position so that this remark may be sounded on his loud speaker. From this point on telephone communication can be carried on between the two operators in the manner described above.

Although definite frequencies have been set forth in the above description, it will be under-

stood that my invention is not limited to these frequencies and that they are given to fix the ideas.

Although I have herein shown and described only one form of apparatus embodying my invention, it is understood that various changes and modifications may be made therein within the scope of the appended claims without departing from the spirit and scope of my invention.

Having thus described my invention, what I claim is:

1. A signaling system for railway trains comprising the combination with a control device having different positions at one location on a train, a mechanism having different conditions at another location on the train, a communication circuit between said locations; of a transmitting means at said one location coupled with said circuit and including a source of carrier current, a receiving means at said other location coupled with said circuit and including a demodulator, a generator capable of supplying different channel frequencies, means governed by the different positions of the control device for modulating the output of said generator with different signaling frequencies, means for impressing the combined output of the generator upon said carrier, a plurality of tuned circuits adapted to be connected with said demodulator and selectively responsive to the different channel frequencies, a detector connected with said tuned circuits, a plurality of signaling circuits controlled by said detector and selectively responsive to the different signaling frequencies, means governed by the signaling circuits for establishing the different conditions of the mechanism, a manually operated selector at each location for selecting a corresponding frequency of said generator and tuned circuit respectively to establish a characteristic channel frequency, and a manually operated means for governing the control device to establish the different conditions of said mechanism.

2. A signaling system for railway trains comprising the combination with a control device having different positions and a mechanism having different conditions at each of two locations on a train, a communication circuit between said locations and a transmitting and a receiving means at each location alternately coupled with the circuit; of a source of carrier current for each transmitting means, a demodulator for each receiving means, a generator at each location capable of supplying different channel frequencies, means governed by the different positions of each control device for modulating the output of the associated generator with different signaling frequencies, means for impressing the combined output of the generator upon the carrier, a group of tuned circuits connected with each demodulator and selectively responsive to the different channel frequencies, a detector connected with each group of tuned circuits, a plurality of signaling circuits controlled by each detector and selectively responsive to the different signaling frequencies, means governed by the signaling circuits for establishing the different conditions of the associated mechanism, a manually operated selector at each location for selecting a frequency of the generator and a tuned circuit at its respective station to establish a characteristic channel frequency for the train, and a manually operated means at each location for governing the control device to establish the different conditions of the mechanism at the other location.

3. A signaling system for railway trains including, a communication circuit connecting two spaced locations on a train, a source of carrier current at one location coupled with said circuit, a generator adapted to generate different intermediate frequencies, a control device adapted to modulate the output of the generator with different low frequencies, means for impressing the output of the generator upon the carrier to effect double modulation of said carrier, a receiving means at the other location coupled with the circuit and including a demodulator, a plurality of tuned circuits adapted to be connected with said demodulator and selectively responsive to different intermediate frequencies, a detector influenced by said tuned circuits, a plurality of control circuits controlled by the detector and selectively responsive to different low frequencies, a mechanism having different conditions governed by the control circuits, a manually operated selector at each location for selecting a corresponding intermediate frequency and tuned circuit at the two locations respectively, and a manually operated means for selecting the different low frequencies to influence a corresponding control circuit to establish a given condition of said mechanism, whereby a characteristic channel frequency can be selected for each of a plurality of different trains and each train equipped with a control system having a plurality of different conditions.

4. A signaling system for railway trains including, a communication circuit connecting two spaced locations on a train, a source of carrier current at one location coupled with said circuit, a generator adapted to generate different intermediate frequencies, a control device adapted to modulate the output of the generator with a given low frequency, means for impressing the output of the generator upon the carrier to effect double modulation of said carrier, a receiving means at the other location coupled with the circuit and including a demodulator, a plurality of tuned circuits adapted to be connected with said demodulator and selectively responsive to different intermediate frequencies, a detector influenced by said tuned circuits, signaling means controlled by said detector and selectively responsive to said given low frequency, and a manually operated selector at each location for selecting a corresponding intermediate frequency and tuned circuit at the two locations respectively whereby a signaling system having a characteristic channel frequency can be provided for each of a plurality of different trains.

5. A signaling system for railway trains including, a traffic track, a train, a source of carrier frequency current, a first generator adapted to supply different intermediate frequencies, a second generator adapted to supply different low frequencies, a control device having different positions for selecting the frequency of the second generator, a first manually operated selector having different positions for selecting the frequency of the first generator, means for double modulating the carrier with the outputs of said generators, means for suppressing the carrier and one side band, coding means for supplying periodic impulses of the remaining side band to the traffic track, receiving means mounted on the train in inductive relation with the traffic track and including a demodulator, a code following relay and a plurality of tuned circuits controlled by the demodulator, said circuits selectively responsive to the different intermediate frequencies, a second

manually operated selector having different positions for selecting the tuned circuit corresponding to the selected frequency of the first generator, signaling circuits influenced by the selected tuned circuit selectively responsive to the different low frequencies, and means controlled by the code following relay for governing the receiving means.

6. A signaling system for railway trains including, a communication circuit connecting two spaced locations on a train, receiving and demodulating means at one location coupled with said circuit, a telephone receiver and a plurality of tuned circuits controlled by said demodulating means and selectively responsive to different intermediate frequencies, a detector adapted to be influenced by any one of said tuned circuits, a plurality of control circuits governed by the detector and selectively responsive to different low frequencies, a mechanism having different operating conditions selectively governed by said control circuits, a manually operated selector for selecting any one of said tuned circuits, a manually operated switch for connecting either the telephone receiver or the selected tuned circuit with said demodulating means, a source of carrier current at the other location coupled with said communication circuit, telephone means adapted to modulate said carrier with voice frequencies, a generator adapted to impress upon said carrier different intermediate frequencies, control means for modulating the output of said generator with different low frequencies, a manually operated selector at said other location for selecting the frequency of said generator, a manually operated means for selecting the low frequency, and a manually operated switch for connecting either the telephone means or the generator with said carrier, whereby telephone communication or a control operating on a distinctive intermediate frequency for effecting the different conditions of the mechanism can be established between said two locations.

7. A signaling system for railway trains including, a communication circuit connecting two spaced locations on a train, a source of carrier current at one location coupled with said circuit, a telephone transmitter for modulating the carrier with voice frequencies, a generator adapted to supply different intermediate frequencies, control means adapted to modulate the output of said generator with different low frequencies, means for modulating the carrier with the output of said generator, a demodulator at said other location coupled with the communication circuit, a telephone receiver and a plurality of tuned circuits controlled by the demodulator, said tuned circuits selectively responsive to the different intermediate frequencies, a detector influenced by said tuned circuits, a plurality of signaling circuits controlled by the detector and selectively responsive to said different low frequencies, a manually operated selector at each location for selecting a corresponding intermediate frequency and tuned circuit at the two locations respectively, a manually operated means for selecting the different low frequencies for influencing a corresponding signaling circuit, a manually operated switch at said one location for rendering active either the telephone transmitter or the generator, and a manually operated switch at the other location for rendering active either the telephone receiver or the tuned circuits, whereby either telephone communication or an automatic control can be established between the two locations.

8. A signaling system for railway trains comprising the combination with the usual engineer's brake valve on the locomotive, an auxiliary brake controlling mechanism located at another point 5 on the train adapted to reproduce different operating functions of the engineer's valve and a communication circuit connecting the two locations; of a source of carrier current, a generator adapted to supply any one of several different 10 intermediate frequencies, means for modulating the output of said generator with different low frequencies according to the position of the engineer's brake valve, means for modulating the carrier with the output of said generator, means 15 for supplying a side band of the double modulated carrier to said circuit, receiving means at said other location coupled with said circuit including a demodulator, a plurality of tuned 20 circuits governed by the demodulator and selectively responsive to the different intermediate frequencies, control circuits governed by the tuned 25 circuits and selectively responsive to the different low frequencies for causing the auxiliary brake controlling mechanism to register with the engineer's valve, and a manually operated selector at each of the two locations for selecting a corresponding intermediate frequency and 30 tuned circuit respectively whereby a channel of a characteristic frequency can be provided for each of several trains.

9. A signaling system for railway trains comprising the combination with a source of carrier current, a telephone receiver, a telephone transmitter, a signaling device having different 35 positions and a control device having different positions at each of two spaced locations on a train; of a first generator at each location adapted to supply different frequencies within the voice frequency range, a second generator at each 40 location adapted to modulate the output of the first generator with different low frequencies according to the position of the control device, transmitting means at each location for modulating the carrier with the combined output of the first generator and then suppressing the carrier and one side band, receiving means at each 45 location responsive to such transmitted side band and including a demodulator, a plurality of

tuned circuits adapted to be connected with each demodulator selectively responsive to the frequencies of said first generator, signaling circuits governed by the tuned circuits for controlling the signaling device and selectively responsive to the different low frequencies, coding means partly at each location for automatically exchanging impulses of the transmitted side band between the two locations for causing the signaling device at each location to register with the position of the control device at the other location, a manually operated selector at each location to select a corresponding frequency of the first generator and tuned circuits for establishing a characteristic channel frequency for the train; and a manually operated master switch at each location for rendering the coding means, first generator and tuned circuits ineffective and for connecting the telephone transmitter and receiver with the carrier source and demodulator respectively for establishing telephone communication. 10 15 20 25

10. In combination with a railway having a plurality of railway trains, a signaling mechanism for each train having a plurality of different positions; and a non-interfering control system for controlling the signaling mechanism of each train including, a source of carrier current, a generator adapted to supply different channel frequencies, control means for modulating the output of said generator with different low frequencies corresponding to the different positions of the signaling mechanism, means for modulating the carrier with the combined output of the generator and then suppressing the carrier and one side band, receiving means influenced by the remaining side band, a demodulator controlled by the receiving means, a plurality of tuned circuits adapted to be connected with the demodulator and selectively responsive to the different channel frequencies, signaling circuits governed by the tuned circuits selectively responsive to the different low frequencies for causing the signaling mechanism to register with said control means, and selecting means for establishing a corresponding channel frequency and tuned circuit. 30 35 40 45

ANDREW J. SORENSEN.
